INVENTOR:

Eugène H. M. E. Durand

BY

ATTORNEY

UNITED STATES PATENT OFFICE.

EUGÈNE HENRI MARIE EMILE DURAND, OF PARIS, FRANCE.

KNITTING NEEDLE.

Application filed August 24, 1923. Serial No. 659,229.

To all whom it may concern:

Be it known that I, EUGÈNE HENRI MARIE EMILE DURAND, a citizen of the Republic of France, residing at Paris, Department of Seine, France, have invented certain new and useful Improvements in Knitting Needles, of which the following is a specification.

This invention relates to improvements in needles for knitting machines, and more particularly in those of the type called latch needles, for the purpose of making it possible at will during the course of manufacture of a knitted article to transfer the loops from a certain number of needles to the adjoining needles by means of simple movements and without the assistance of intermediate apparatus such as transfer punches.

These improvements chiefly consist in providing in an ordinary knitting or frame needle a recess adapted to receive a part (head or hook) of a second similar needle constituting, with the first one, a deformable unit of sufficient thinness and smoothness at its working part, in such a manner that the mesh or loop formed on the first needle can successively slide from the latter on to the unit formed by it and the second needle—on which there may or may not be a loop already—the head of said second needle having been inserted in the recess provided in the first needle, and remain on the second one.

In order to make the following explanation clearer, the accompanying drawing shows by way of example a knitting or frame needle provided with the improvements according to the invention.

Figure 1 is a side elevation of the improved needle, of which Figure 2 is a back view, and Figure 3 a section on line 3—3, Fig. 1. Figures 4 to 8 show the respective positions of the two needles during the landing operation.

45 *m* is the shank of an ordinary knitting needle. This shank may have a heel *b* or any other suitable driving device, a hook *c* and a tumbler or latch *d*.

As already stated at the beginning of the present specification, the essential characteristic of the invention consists in a recess provided in the needle and intended to receive a second needle similar to the preceding one. This recess is shown at *e*, and the

outline of the second needle *n* is shown in 55 Figure 1, in dotted lines, it being understood of course that the said second needle can occupy various positions either above or below that shown, without coming out of the recess *e*.

The said recess *e* must not in any way be confused with the recess *g* for the play of the latch *d*, which recess in the ordinary knitting needle scarcely reaches the back of the needle.

The position of the above mentioned recess *e* such as it is shown in the drawing, now seems to be the most advantageous one when it is a question of latch needles.

The device just described is utilized in 70 the following manner:

Assuming that there are two adjoining needles *m* and *n* occupying the position shown in Figure 4 where they pass exactly one behind the other, the loops *o* and *p* pull 75 on the fabric *q* which is securely held in place by any desired means, for instance by means of a comb. The needle *m* is raised whilst the needle *n* is brought behind the preceding one (Figure 5) as shown on a 80 larger scale in Figure 1.

The upward movement of the needle *m* continuing, the movement of the needle *n* is started; the latter will get into the loop *o* which is drawn downwards by the whole of 85 the fabric and has left the hook of the needle *m* in order to pass on the shank (Figure 6). If now the needle *m* is lowered whilst the needle *n* continues to rise, the loop *o* will pass from the hook of the needle *n* on to the 90 shank of the same, whilst the loop *p* will close the latch of the descending needle *m* (Figure 7) which will finally escape from its loop which it will leave on the shank of the needle *n*, by the side of the loop which is 95 already there (Figure 8).

The transfer of the loop from a needle to the next one (whether the latter has or has not its own loop) will thus have been effected without an intermediate apparatus, 100 which is the object of the invention.

I claim as my invention:

1. A latch needle, having a hook at one end, a recess at the foot of the hook, and a latch mounted in said recess; said needle 105 being also formed with a second recess which is located immediately adjacent the first recess but is independent thereof, and which

is designed to receive the hook of a second needle similar to, and extending in the same direction as, the first one, thereby to enable the inter-fitted ends of the two needles to jointly constitute a relatively thin and smooth deformable unit onto which a loop formed on the first needle may slide therefrom, such loop being thereafter left on the

second needle when the first needle is withdrawn.

10

2. A latch needle, according to claim 1, in which the second-named recess is formed in the back of the needle directly opposite the first needle.

In testimony whereof I affix my signature.

EUGÈNE HENRI MARIE EMILE DURAND.
